UNITED STATES PATENT OFFICE.

WILTON H. SPENCER, OF PROVIDENCE, RHODE ISLAND.

LOOM-SHUTTLE.

SPECIFICATION forming part of Letters Patent No. 340,463, dated April 20, 1886.

Application filed July 11, 1885. Serial No. 171,239. (No model.)

To all whom it may concern:

Be it known that I, WILTON H. SPENCER, of the city of Providence, in the county of Providence and State of Rhode Island, have 5 invented a new and useful Improvement in Loom-Shuttles, of which the following is a full, clear, and exact description, reference being had to the accompanying drawings, forming a part of this specification, in 10 which—

Figure 1 represents an isometrical perspective view showing the spindle in position for use. Figs. 2 and 3 are detached perspective views showing the spindle and the supporting-frame therefor, the spindle being represented in different positions.

My invention relates to that class of loom-shuttles in which split spindles for holding cops are employed; and it consists in a novel 20 construction of parts, by means of which the spindle is expanded and caused to more effectually hold the cop when the shuttle is in use, which insures a continuous even supply of the yarn while the shuttle is in motion throughout 25 the entire unwinding of the cop or yarn, and whereby the spindle is securely locked in position in the shuttle-body when depressed, as hereinafter described and claimed.

In the accompanying drawings, A, Fig. 1, 30 represents the body of the shuttle; B, the spindle; and C, Fig. 2, the frame in which the spindle is made to operate. The spindle B is a split spindle—that is to say, is composed of two parts, joined at one end to form the point, 35 the opposite or heel ends being separate. It is pivoted a suitable distance from one end of frame C, and the tapering arms e e', Fig. 3, of the heel portions are slightly bent sidewise at or near the pivot-hole and diverge laterally 40 to their extended ends. The frame C is constructed of a square form, having a bottom and two sides, of which each side is provided with a lip, d, at its top edge, Fig. 3, said lips being turned inward and operating to bring 45 the arms e e' firmly together when the latter are pressed in between the lips in lowering the spindle, as shown in Fig. 2, and forming beneath them a space for the springs n n. Said springs are fitted lengthwise in frame C, one 50 under each of the aforesaid lips, and they are held in place by the pin a passing through one

of the ends of each. The spindle B is placed between the springs n n, as shown in Fig. 2, and the frame C is let into the body A of the shuttle at one end to remain fixed therein, and 55 the whole as arranged are pinned in the end by pin a, Fig. 1.

From the foregoing the nature and the operation and advantages of my invention will be plainly seen and understood to all familiar 60 with the working of that class of shuttles referred to. When the point end of the spindle is elevated, as shown by dotted lines in Fig. 1, the arms e e' are withdrawn from the frame C, as shown in Fig. 3, and the expansive sides of 65 the body of the spindle, from the point of the spindle rearward to the pivot-hole at a, will be permitted to come in close proximity to each other, and the cop may readily be placed in position thereon without disarranging or, 70 as it is termed, "stabbing" the cop or causing waste. If the spindle is now depressed, the cop being on the same, the arms e e' are brought in between the lips d d, pressing them rigidly together, and so holding them, thereby 75 forcing the expansive sides of the spindle apart laterally, and firmly securing the cop in place for use, Fig. 2. The springs n n have their free ends formed with ridges upon their inner 80 sides, and the ends of the arms e e' are provided on their outer sides with corresponding grooves. When the spindle is depressed, as aforesaid, the ridges spring into their respective grooves, by which arrangement said spindle B is retained in the body A of the shuttle without 85 the use of the ordinary spindle-locking spring.

An advantage in my improvement, which I have demonstrated by actual experiment, is that when the arms e e' are passed in between 90 the side lips of frame C and are held together rigidly therein, the expanded sides of the body of the spindle are certain and uniform in their action in holding the cop throughout the entire unwinding of the yarn.

I am aware that a solid spindle has been constructed with a split heel, the wedge-shaped portions of which have been fitted between the upwardly-converging sides of a supporting-frame intended to be applied to a shuttle-body 100 to hold the spindle in position when depressed, and this I do not claim.

My improved construction not only secures the effective holding of the spindle in its depressed position, but effects the expanding of the body of the spindle.

5 Having thus described my invention and its use, what I claim is—

The split expanding spindle B, formed with diverging heel portions grooved on their outer sides, substantially as described, in combina-

tion with the frame C, having the lips d d, and the separate springs n n, adapted to engage with the said grooved heel portions, substantially as specified.

WILTON H. SPENCER.
